The ornamental design for a coding matrix tool, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a first perspective view of a coding matrix tool in unfolded configuration showing my new design;

FIG. 2 is a second perspective view thereof;

FIG. 3 is an elevation view of a first matrix sheet or panel thereof;

FIG. 4 is an elevation view of a second matrix sheet or panel thereof;

FIG. 5 is an elevation view of a third matrix sheet or panel thereof;

FIG. 6 is an elevation view of a fourth matrix sheet or panel thereof;

FIG. 7 is an elevation view of a fifth matrix sheet or panel thereof;

FIG. 8 is an elevation view of a sixth matrix sheet or panel thereof; and,

FIG. 9 is an elevation view of a seventh matrix sheet or panel thereof.

The broken lines in the figures represent portions of the coding matrix tool which are not part of the claimed design.
